UNITED STATES PATENT OFFICE

CECIL CHARLES BRINTON, OF KIDDERMINSTER, ENGLAND

LOOM FOR WEAVING AXMINSTER CARPETS AND SIMILAR TUFTED FABRICS

Application filed May 18, 1929, Serial No. 364,179, and in Great Britain May 22, 1928.

This invention has reference to looms for weaving Axminster carpets and similar tufted or pile fabrics and comprises certain improvements as hereinafter described which may be utilized to obviate a disadvantage attending the weaving of single-colour fabrics in looms as ordinarily constructed wherein the occurrence in the frame of a tuft-yarn or yarns varying (throughout the whole or part of its or their length) in shade from the proper or selected colour, results in the production of a streaky or unevenly coloured fabric; the streakiness resulting from the weaving into the fabric of a line or lines of tufts cut from the faultily-shaded yarn or yarns.

In an ordinary single-colour loom of the type known as the Brinton Axminster loom, streakiness arising from yarn-shade variations cannot be remedied during weaving due to the fact that each tuft gripper of the loom always picks up its tufts of the pile-yarn from the same yarn-carrier, so that if the yarn proceeding from any particular carrier shows a difference in shade, or varies in shade in a part or parts of its length, the production of a corresponding streak, or a line or lines of incorrectly-shaded tufts, in the carpet is inevitable.

Further it is the common practice in single-colour weaving in a Brinton type Jacquard loom, to run each of the yarns through a yarn-carrier which is suspended from the jacquard mechanism, but to work the loom with the jacquard out of action. These suspended carriers are, however, incapable of controlled lateral step-by-step displacement and to enable such displacement for the purposes of the present invention the loom is provided with a unitary yarn-carrier comprising a series of side-by-side compartments, through each of which a single yarn is passed, and also with mechanism which during each loom cycle changes the lateral relationship of the yarn-carrier unit to the tuft-grippers, or vice versa, so that each gripper is constrained or enabled over a given series of cycles successively to pick yarn-tufts from a series of different yarns.

Thus, in the event of any particular yarn

being defectively shaded, the mechanism ensures a certain distribution of tufts cut from that yarn so that instead of the defective tufts being repeated in the same line and producing an obvious streak or fault, 55 they are planted in the fell of the cloth in echelon, or in a different tuft-line and also in a different tuft row, throughout a series of cycles, and being thus separated and distributed amongst a number of different rows 60 of correctly-shaded tufts, the defective tufts are rendered practically unnoticeable.

An application of the invention to a tuft-distributing mechanism for a Brinton-type Axminster loom, in which the position of the yarn-carrier block is changed laterally in relation to the grippers step-by-step over a series of loom cycles, is shown by way of example in the accompanying drawings, in which

Figure 1 is an elevation of a part of the loom showing the general lay-out of the tuft distributing mechanism.

Figure 2 is another elevation but showing the laterally-displaceable yarn-carrier in section and illustrating the disposition of the said carrier in relation to the tuft-grippers.

Figure 3 is a side elevation, on a smaller scale than Figures 1 and 2, of a part of the loom showing the arrangement adopted for actuating or controlling the displaceable yarn-carrier block.

Figure 4 is another elevation, viewed from the front of the loom, showing the arrangement of the block-displacing and return mechanism in relation to the frame of the loom.

Figure 5 shows a separate plan of the indexing cam-gear controlling the unitary yarn-carrier.

Figure 6 is a separate plan of the carrier-block return mechanism.

The same letters of reference indicate corresponding parts in the several figures.

The tuft-forming and planting mechanism of the loom shown in the drawings is of the well-known Brinton Axminster type in which, during each cycle, a system of mechanically-controlled grippers grip the ends of the yarn projecting from the compart-

ments in the block *c*, withdraw the yarn a certain distance and, after the withdrawn ends have been cut off into tufts, the grippers back away from the yarn carriage and plant their tufts in the fell of the cloth. On the tufts being locked in the fell, the grippers open to release the planted tufts and are taken back to the yarn carriers to commence a fresh cycle.

In the loom as shown, the grippers are mounted in an ordinary carriage; that is to say, in a carriage which has no lateral movement in the frame, but to enable tuft distribution in accordance with the present invention, the yarn-carrier consists of a block *c* having a series of side-by-side compartments through each of which a single yarn is passed from the yarn-carrier and the block is mounted so as to be capable of lateral or transverse movement relative to the frame and the gripper carriage, and cam and spring mechanism is embodied for shifting the carrier-block in a series of steps, in relation to the gripper-system (one step to each cycle) and periodically, or after completion of the predetermined number of cycles, returning the said unitary yarn carrier to the zero or starting position. The yarn carrier is provided with at least three more yarn compartments than there are grippers.

The loom illustrated embodies a four-step distributing cam *d* whose operations are so controlled that, considering any group of four adjacent yarn-carrier compartments in the block, the mechanism will, at the start of each cycle of the loom, shift the carrier-block laterally to a distance equivalent to the pitching of the grippers and present each compartment of the carrier to a gripper next removed from the gripper that extracted a tuft from the said compartment in the preceding cycle. Thus, during four successive loom cycles, each yarn carrier compartment presents its yarn successively to four different grippers, enabling the echelon planting of tufts extracted and cut from that yarn in four different lines of the weave, whilst on completion of the prescribed series of four carrier-block displacements, the automatic return mechanism shifts the carrier-block back to the zero position permitting the commencement of another series of tuft-distributing operations in the next cycle of the loom.

The yarn-carrier block is mounted in its housing at the back of the gripper mechanism (see Figure 2) so as to be capable of displacement to and fro in the width of the loom and the tuft-distributing cam consists of a vertically-displaceable slide or member *d* suitably mounted in guides on the left-hand side of the loom with a four-step cam surface *d*¹, *d*², *d*³, *d*⁴, presented inwardly or towards the yarn-carrier block, enabling an extension *c*¹ from the end of the said block to be maintained in contact with the said cam surface

by the action against the block of suitably-applied loading springs or equivalent expedients (not shown in the drawings). The cam-member is connected to a mechanism, driven by suitable gearing, which drops or depresses the same by a series of steps or stages corresponding to the number of steps in the cam, and then (after the carrier-block has been positively shifted back to its starting point) restores the said member also to its zero or starting position. The cam-surfaces *d*¹, *d*², *d*³, *d*⁴, are arranged successively in receding perpendicular planes and are pitched, as regards their lateral spacing, to correspond with the pitching of the yarn-carrier compartments and grippers of the loom, and since each downward displacement of the said cam-member presents a different and stepped-back plane surface to the extension of the spring-loaded carrier-block, the mechanism enables the yarn carrier block to be spring-shifted laterally at each such step (towards the left of the loom) through a distance equivalent to the pitching of the grippers, and to be returned to its starting point on completion of the series of four step-displacements to enable the next tuft-distribution cycle to be started.

The depression and return motions of the tuft-distribution cam may be realized by coupling the same, by a rod or link *f*, to an overhead lever or rocking bar *g* which is itself controlled by a four-step cam *h* keyed to a vertical gear-driven shaft *h*¹ mounted at the side of the loom, whilst to provide for the return of the yarn-carrier block to zero and clear the way for the lifting of the distributing cam to its starting position, a thrust-rod or slide *i* may be arranged horizontally in the loom with one end in contact or connection with the yarn-carrier block and its other end coupled to a lever *i*² arranged in the path of a suitably-driven return-cam *i*³ having a single lift timed to displace the thrust-rod and yarn-carrier block to the right, and against the block-loading springs, immediately the distribution cam member has completed its operative movement. The carrier-block return-cam *i*³ may be driven off the same shaft *h*¹ as the block-displacing cam *h* and may be mounted, on a carrier member *i*⁴ that is keyed to the said shaft *h*¹; the connection between the cam and its carrier being such as will permit of the cam being shifted angularly around the shaft to radially adjust its lift for timing the return-displacement of the yarn-carrier block relative to the return displacement of the tuft-distributing cam.

Having described my invention what I claim and desire to secure by Letters Patent is:

1. A loom of the kind referred to, comprising a unitary yarn-carrier, having a series of side-by-side compartments therein through each of which a single yarn is passed, a series

of tuft grippers co-operating with said yarn-carrier, and means for changing the lateral relationship of the yarn-carrier to the series of tuft grippers whereby each gripper, over a given series of loom cycles, successively picks yarn-tufts from a series of different yarns.

2. A loom of the kind referred to, comprising a unitary yarn-carrier adapted to accommodate a plurality of yarns, a series of tuft grippers co-operating with said yarn-carrier, a multiple stepped cam, means for moving said cam intermittently through a series of distances each equal to one step of the cam and means whereby said cam changes the lateral relationship between the yarn-carrier and the tuft-grippers during each cycle of operations of the loom so that each gripper, over a series of loom cycles corresponding to the number of cam-steps, successively picks tufts from a series of different yarns.

In witness whereof I affix my signature.
CECIL C. BRINTON.
